UNITED STATES PATENT OFFICE.

HENRY D. JAMES, OF EDGEWOOD PARK, PENNSYLVANIA, ASSIGNOR TO WESTINGHOUSE ELECTRIC & MANUFACTURING COMPANY, A CORPORATION OF PENNSYLVANIA.

MOTOR-CONTROL SYSTEM.

Original application filed March 13, 1920, Serial No. 365,467. Divided and this application filed August 22, 1922. Serial No. 583,502.

To all whom it may concern:

Be it known that I, HENRY D. JAMES, a citizen of the United States, and a resident of Edgewood Park, in the county of Allegheny and State of Pennsylvania, have invented a new and useful Improvement in Motor-Control Systems, of which the following is a specification, this application being a division of copending application

Serial No. 365,467, filed March 13, 1920.

My invention relates to motor-control systems and particularly to such systems as are employed to effect the dynamic braking of series electric motors.

One object of my invention is to provide a dynamic brake for rapidly diminishing the speed of rotation of a series electric motor with the least possible wear and injury thereto.

A second object of my invention is to provide a system wherein a master switch may be quickly thrown from an operative position to a position corresponding to the reverse direction of operation of the motor without injury thereto.

In a system embodying my invention, the same number of contactors are employed as are used with a standard reversing controller, and dynamic braking is effected by employing a dynamic braking circuit which includes a resistor, switches that coact with the directional switches, a main-line switch, and a circuit including a switch which may coact with the directional switches or the main-line switch for energizing the series field magnet winding during dynamic braking.

In the accompanying drawing, Fig. 1 is a diagrammatic view of circuits and apparatus embodying my invention;

Fig. 2 is a schematic diagram corresponding to Fig. 1, and

Fig. 3 is a sequence chart indicating the sequence of operation of the several contactors provided for controlling the respective circuits and apparatus shown in the drawing.

Referring to the drawing, line conductors 1 and 2, which may be connected to any suitable source of energy, supply current to an electric motor, the armature of which is indicated at 3 and which has a series field-magnet winding 4. A starting resistor 5 is in series with the motor. If it is so desired,

a portion or all of the resistor 5 may be shunted during the normal operation of the motor, but such arrangement is not material to the present invention.

The direction of operation of the motor is controlled by the directional switches 6, 7, 8 and 9. A dynamic-braking circuit comprises a pair of auxiliary switches 10 and 11 which are mechanically interlocked with reversing switches 6 and 7, respectively, and resistors 12. A main-line switch 13 is provided with an operating coil 14.

A master switch 16 comprises electrically-connected contact segments 17, 18 and 19 that respectively engage contact fingers 20, 21 and 22, when they are moved to forward position "a," thereby energizing actuating coils 23, 24 and 14 of the respective switches 9, 7 and 13. The contact finger 22 is supplied with electrical energy from the line conductor 1. Contact fingers 22, 25 and 26 respectively coact with electrically-connected contact segments 27, 28 and 29 to control the actuating coils 30 and 31 of switches 8 and 6, respectively, in the reverse position "C."

The dynamic-braking switches 10 and 11 have holding coils 32 and 33, respectively. Switches 40 and 41 are mechanically interlocked, respectively, with reversing switches 8 and 9. By means of the auxiliary switch 40, the control circuit, which includes contact finger 26 and the coils 31 and 14, cannot be completed until the switch 8 is closed. As the coils 31 and 14 respectively actuate switches 6 and 12, it is impossible to close switch 6 without first closing switch 8 and, if switch 6 is closed, switch 13 must be closed. In a similar manner, switch 41 prevents switch 7 from closing until switch 9 is closed and, if switch 7 is closed, switch 13 must also be closed.

When the master switch is in position "a," the contact segments 17, 18 and 19 are engaged, respectively, by contact fingers 20, 21 and 22, and thus the coils 23, 24 and 14 are energized to close directional switches 9 and 7 and the line switch 13, thereby causing the motor to rotate in the reverse direction. Dynamic-braking switch 11 is opened by the closing of the switch 7, and the reversing switches 6 and 8 are held open by gravity when the coils 31 and 30 are not energized.

If the master switch be moved to posi-

tion "e," which is both the drift and the off position, the contact fingers 20, 21 and 22 are disengaged from the corresponding contact segments 17, 18 and 19, thereby de-energizing coils 23, 24 and 14, and thus opening switches 9, 7 and 13. In this position, the dynamic-braking switches 10 and 11 only are closed.

If it is desired to employ the motor for 10 dynamic braking, when the armature 3 is rotating in the reverse direction, the master switch is moved to position "d." In this position, the contact fingers 22 and 25 engage contact segments 27 and 28, thereby 15 energizing coil 30, which actuates reversing switch 8. The dynamic-braking switches 10 and 11 being closed, as well as directional switch 8, a complete generator circuit is established. The current generated by the 20 armature 3 traverses a circuit comprising the switch 8, the winding 4, the resistor 12 and the switch 10 to the armature 3, and also through a second circuit comprising the switch 11, both banks of resistance 12 and 25 the switch 10 to the armature 3. The electrical energy generated by the motor is expended in the resistors 12.

By moving the master switch from position "d" to position "e," the circuits are arranged for the forward direction of rotation of the motor. The contact finger 26 engages the contact segment 29, thus energizing coils 31 and 14, which actuate switches 6 and 13. The switches 6, 8 and 13 being closed, and 35 the remaining switches being open with the exception of the dynamic-braking switch 11 and the auxiliary switch 40, the motor rotates in a forward direction.

If dynamic braking is desired, when the 40 motor is rotating in a forward direction, the master switch is moved in a reverse direction from position "e" to position "b." All of the switches, except dynamic-braking switches 10 and 11, are released as the contact fingers pass through the "off" position "c." At position "b," the contact fingers 20 and 22 engage the contact segments 17 and 19, thereby energizing the actuating coil 23 and closing the switch 9.

I have invented a system of control in which a series motor may be permitted to drift before dynamic braking is applied. This order in the sequence of operation of the motor is desirable, for the operator of 55 a car or machine, by permitting the motor to drift and then applying dynamic braking, can bring the car or machine to a stop nearer a predetermined point, than, if dynamic braking first occurs. It is apparent that 60 power and wear on the equipment are lessened by having drifting precede dynamic braking of the motor.

In this system, dynamic braking is secured 65 without "plugging" the motor. Therefore, the car or machine will not reverse its direc-

tion after coming to a complete stop, as would occur in the systems of control for series motors formerly employed.

I have shown the dynamic braking positions of the master switch nonadjacent to 70 their corresponding operative positions, therefore, dynamic braking does not occur, if the master switch is slightly removed from one of the operative positions and the direction of operation of the motor can be 75 quickly changed by continuing the movement of the master switch to its next position.

From the construction and operation of 80 my control system herein described, it is apparent that the principal advantages are the simplicity of control from the master switch and that quick dynamic braking is secured.

While I have shown a preferred form of 85 my invention, it is apparent that slight modifications may be made without departing from the spirit thereof, I desire, therefore, to be limited only by the scope of the appended claims.

I claim as my invention:

1. The combination with an electric motor 90 having a series field magnet winding, of a dynamic braking resistor and means for connecting the resistor and field-magnet winding in shunt relation during dynamic braking.

2. The combination with an electric motor 95 having a series field-magnet winding and electro-responsive controlling means therefor, of a normally closed dynamic-braking 100 circuit and means comprising said controlling means for connecting the field-magnet winding into the braking circuit.

3. The combination with an electric motor 105 having an armature, and a field-magnet winding, of electro-responsive controlling means therefor, a plurality of dynamic braking resistors normally in circuit with the armature, and means comprising said controlling means for connecting the field-magnet 110 winding, selectively in circuit with said resistors.

4. In a motor-control system, the combination 115 with a series motor having an armature and a field-magnet winding, and directional switches therefor, of means for connecting said armature and said field-magnet winding in a dynamic braking circuit comprising only one of the said directional switches.

5. In a motor-control system, the combination 120 with a series motor having an armature and a field-magnet winding, and directional switches therefor, of means for connecting said armature and said field-magnet winding in a dynamic braking circuit comprising only one of the said directional switches, said motor during dynamic braking 125 being independent of an external source of energy.

6. In a motor-control system, the combi-

- nation with a series motor having an armature and a field-magnet winding and directional switches therefor, of a dynamic-braking circuit comprising said armature for
 5 effecting dynamic-braking thereof, and a plurality of switches coating with said directional switches for controlling said circuit, and so connecting said braking circuit through only one of said directional
 10 switches to said field-magnet winding that said winding is energized by said braking circuit.
7. In a motor-control system, the combination with a series motor having a field-
 15 magnet winding, a plurality of directional switches for controlling the direction of operation of said motor, and a dynamic-braking circuit for said motor, of a circuit including said series field-magnet winding,
 20 and a portion of said dynamic-braking circuit, the direction of the energization of said field magnet winding being controlled by said directional switches.
8. In a motor-control system, the combination with an electric motor, of controlling means therefor comprising a master switch having an inoperative position, operative positions corresponding to the rotation of said motor in a forward and a re-
 25 verse direction and intermediate positions for effecting dynamic braking of said motor, and means controlled thereby in such manner that dynamic braking in one direction is accomplished by said master switch being
 30 actuated through the adjacent intermediate position and said inoperative position to the other intermediate position.
9. In a motor control system, the combination with a motor and means comprising
 35 a plurality of contactors for governing said motor, of a master switch for controlling said contactors and having an inoperative position and operative positions corresponding to the rotation of said motor in a for-
 40 ward and in a reverse direction and intermediate positions for effecting dynamic braking of said motor so arranged that dynamic braking in one direction is accomplished by said master switch being brought to said
 45 intermediate position adjacent to said opposite operative position.
10. In a control system, the combination with a motor and means comprising a plu-
- rality of contactors for governing said motor, of a master switch for controlling said contactors and having operative positions 55 for effecting the forward and the reverse operation of a motor, a central position for effecting drifting and de-energization of said motor and dynamic-braking positions 60 each of which is between said central position and said opposite operative position.
11. In a motor-control system, the combination with an electric motor, of controlling means therefor comprising a master switch having a central inoperative position, an operative position on each side of the inoperative position, said operative positions corresponding to the respective directions of rotation of said motor, and having, also, a position intermediate each operative position 65 and the inoperative position, each of said intermediate positions being arranged to effect dynamic braking of said motor when it is rotating in the direction corresponding to the operative position adjacent to the other 70 intermediate position.
12. In a motor-control system, the combination with an electric motor, of controlling means therefor comprising a master switch having a central inoperative position, 75 a position for effecting dynamic braking of said motor when rotating in the reverse direction, an operative position for effecting forward rotation of said motor, said positions being in the order named from said central position, and similar positions in the same order from said central position for respectively effecting dynamic braking of said motor when rotating in the forward direction and effecting rotation of said motor in the reverse direction. 80
13. In a motor-control system, the combination with a motor having an armature and a series field-magnet winding, of a resistor, 85 a plurality of directional contactors for governing the direction of said motor and means comprising said resistor and only one of said directional contactors for forming two dynamic-braking circuits, each of said circuits comprising different portions of 95 said resistor.

In testimony whereof, I have hereunto subscribed my name this 16th day of August, 1922.

HENRY D. JAMES.
